(57) **CLAIM**

The ornamental design for the iron soleplate, as shown and described.

DESCRIPTION

FIG. 1 is a bottom perspective view of an embodiment of an iron soleplate;

FIG. 2 is a bottom edge view thereof;

FIG. 3 is a side view thereof; and,

FIG. 4 is a bottom view thereof.

The broken lines depict portions of the iron soleplate that form no part of the claimed design.
